E. P. Newton,
Wrench.

Nº 14,249.

Patented Feb. 12, 1856.

UNITED STATES PATENT OFFICE.

ELISHA P. NEWTON, OF GREEN ISLAND, NEW YORK.

WRENCH.

Specification of Letters Patent No. 14,249, dated February 12, 1856.

To all whom it may concern:

Be it known that I, ELISHA P. NEWTON, of Green Island, in the county of Albany and State of New York, have made certain 5 new and useful Improvements in Constructing Slide or Adjustable Wrenches; and I do hereby declare that the following is a full, clear, and exact description of the same, reference being had to the annexed drawings, making a part of this specification, in which—

Figure 1 is a longitudinal sectional view, and Fig. 2 a cross section of the same.

The same letters have reference to like 15 parts in each of the figures.

The nature or principle of my invention consists in combining or arranging with the adjustable or sliding jaw of the wrench a concave semi threaded shank, a convex 20 toothed eccentric catch or stop, the parts being arranged, so that when the semi threads of the shank and eccentric are engaged the sliding jaw is held fast for use, and when the threads are disengaged, the 25 jaw can slide rapidly either way until set in proper position and is then held fast by means of the eccentric.

The construction is as follows, viz: A is 30 the stationary jaw; B, the shank; C, a concave or semi cylindrical recess formed in one side of the shank. This recess is finished with threads.

D is the sliding jaw, being secured to the shank by straps (a) and (b) passing around the same. 35

E is a semi threaded eccentric arranged and operating with and within a recess in the strap (b).

(c) is a thumb piece by means of which, the eccentric with its threads are thrown in 40 and out of gear with those of the shanks, when it is desired to move, or hold the sliding jaw.

Having fully described by improved adjustable wrench, I wish to be understood as 45 not claiming the toothed shank; but

What I consider to be new and desire to claim by Letters Patent is:

The arrangement of a semi-screw-thread cut, or counter sunk, in the shank, and the 50 semi screw-threaded stop or catch, for working therein, by which means finer threads may be used, and the movable jaw be brought closer up to the nut, and the stop or catch removed out of the way of the action of the wrench, they being arranged and operating in the manner as herein described 55 and shown.

E. P. NEWTON.
